Phillips Petroleum Company, a corporation of
Delaware

Application November 8, 1948, Serial No. 58,892

4 Claims. (Cl. 260—673)

1

This invention relates to the production of aromatic hydrocarbons. In one aspect this invention relates to the manufacture of light aromatic hydrocarbons together with relatively minor amounts of diolefinic hydrocarbons and heavier aromatic hydrocarbons. In another aspect this invention relates to a two-stage process wherein a hydrocarbon gas is converted to light aromatic hydrocarbons, such as benzene, toluene, xylene and the like, and to relatively minor amounts of diolefin hydrocarbons and heavier aromatics.

As is well known to the workers in the art, hydrocarbons may be converted into acetylene by a high temperature heat treatment, such as passage through the electric arc, partial combustion at high temperatures, or the like. Temperatures in excess of 2000° F. are necessary to obtain good yields of acetylene, although some acetylene may be formed at much lower temperatures. It is also well known that at an appropriate temperature, say in the range of about 1000 to 1200° F., acetylene polymerizes rapidly to benzene and other normally liquid aromatic hydrocarbons. Therefore, it is possible to convert a gaseous hydrocarbon to normally liquid aromatic hydrocarbons by subjecting a gaseous hydrocarbon to a primary heat treatment, at high temperature, in which acetylene is formed, and then subjecting the acetylene-containing gas product to a secondary heat treatment at a relatively low temperature, such as from 1000 to 1200° F. as already mentioned.

However, in the temperature range of 1000 to 1200° F., the contact time required for formation of economically feasible yields of light aromatic hydrocarbon product is so long as to promote various side reactions, such as polymerization of acetylene product to form high molecular weight cyclic hydrocarbons, and rehydrogenation of acetylene product to ethane. Under such conditions, high and selective yields of light aromatic hydrocarbons are not obtained. In the past, this has been the case even to a larger extent when operating at temperatures higher than 1000 to 1200° F. due to concomitantly increased carbon and polymer formation, resulting in even lower yields of desired product.

This invention is concerned with a two-stage process wherein acetylene product of an acetylene-forming step is converted to light aromatic hydrocarbon product in high and selective yield, at temperatures from 600 to 1000° F. above those ordinarily employed in the manufacture of aromatic hydrocarbons from acetylene, and wherein carbon and polymer formation is substantially prevented.

2

An object of this invention is to provide a process for the manufacture of aromatic hydrocarbons.

Another object is to provide a process for the production of aromatic hydrocarbons from acetylene-containing stocks.

Another object is to utilize temperatures higher than heretofore in the manufacture of aromatic hydrocarbons from acetylene-containing gas.

Another object is to provide a two-stage process for the manufacture of aromatic hydrocarbons wherein an acetylene-containing gas product is formed in a first stage, and is then converted in a second stage to light aromatic hydrocarbons at a temperature within the range of 1800 to 2400° F.

Another object is to provide a process for the conversion of a gaseous hydrocarbon to light aromatic hydrocarbons in selective and high yields, and into relatively minor amounts of valuable by-product diolefins.

Other objects of this invention will be apparent, to one skilled in the art, from the accompanying discussion and disclosure.

In accordance with a preferred embodiment of this invention, light aromatic hydrocarbons, such as benzene and toluene together with relatively minor amounts of other light aromatics, and of diolefin hydrocarbons such as cyclopentadiene, butadiene, and others having from 4 to 6 carbon atoms per molecule, may be prepared in a novel two-stage process. A gaseous hydrocarbon is preheated under minimum cracking conditions, then further heated by admixture with combustion products formed by burning hydrogen or a hydrogen-rich gas with oxygen, and the resulting admixture is maintained in a first stage at its existing high temperature long enough for acetylene formation to take place, but short enough to substantially prevent undesirable dehydrogenation and/or polymerization of acetylene product. In a second stage, the acetylene-containing product is maintained in the presence of hydrogen under conditions of temperature and time favorable for the formation of desired light aromatic hydrocarbon product in high yield.

It is a feature of my invention that light aromatic hydrocarbons are produced from an acetylene-containing gas in high yield at high temperatures, without unduly hydrogenating or dehydrogenating acetylene reactant, whereby a more efficient utilization of the acetylene-containing material is effected. Operating the aromatic hydrocarbon-forming step in the presence of hydrogen at such high temperatures, provides

for shorter required contact times, and under such conditions, I have found that side reactions such as dehydrogenation and/or undue polymerization of acetylene are substantially prevented, and that high yields of desired aromatic hydrocarbons, especially benzene, may be obtained. Higher yields of valuable diolefins hydrocarbon by-products are obtained, than heretofore.

Under the conditions of a preferred embodiment of my invention the aromatic-forming temperatures usually employed vary from 600 to 1000° F. above those usually used for conversion of acetylene stocks to light aromatic hydrocarbons, and although they may favor some hydrogenation of acetylene reactant to ethylene, which may be advantageous, they are above those at which any substantial rehydrogenation of acetylene or ethylene to ethane will occur. The presence of hydrogen in the aromatics-forming step inhibits undue dehydrogenation and polymerization of acetylene reactants.

Fresh hydrocarbon gas to be converted to the desired aromatic product is preheated in a pebble heater-type apparatus, which in a preferred embodiment of my invention, usually comprises a series of substantially vertically-extending zones, often in vertical alignment with each other. Usually two such zones are employed and are connected by a relatively narrow connecting zone, or throat. The top or upper zone is commonly referred to as the pebble heating chamber and the lower zone as the gas reaction or gas heating chamber. A combustion zone, or chamber, is positioned adjacent or in close proximity to the sides of the lower portion of the heating chamber. Combustion gas from a combustion chamber is passed through the mass of pebbles in the pebble heating chamber. A contiguous mass of particulate contact material, often referred to as pebbles, fills the pebble heating zone, the interconnecting zone or throat, and the gas reaction or heating zone, and flows downwardly through these zones by gravity. Pebbles are discharged from the bottom of the gas reaction zone at a controlled rate, and returned, usually by elevating means, to the inlet in the upper portion of the pebble heating zone. A contiguous moving pebble mass thereby fills the pebble heating zone, gas heating zone, and the interconnecting zone or throat at all times.

The term "pebble" as used in this specification denotes any refractory material in fluent form, size, and strength, which will flow readily by gravity through the various chambers of a pebble heater apparatus. Pebbles are preferably, substantially spherical and are about $\frac{1}{2}$ " to 1" in diameter, the preferred range being about $\frac{1}{4}$ " to $\frac{1}{2}$ ".

In the following description, one method of operating my process will be specifically disclosed. The figures are diagrammatic illustrations of apparatus in which my process may be practiced. It is to be understood that the flow diagram is diagrammatic only and may be altered in many respects, by those skilled in the art, and yet remain within the intended scope of my invention.

Referring then to Figure 1, pebble heating zone 14 and gas heating zone 11 are insulated chambers, each containing a contiguous fluent mass of pebbles 9 and connected by a heat insulated conduit, forming pebble throat 16. Conduits 7 and 8 serve as pebble inlet and outlet for chambers 14 and 11, respectively. Star valve (or other type of pebble feeder) 18 regulates the rate of flow

of pebble mass 9, through chamber 14, throat 16 and chamber 11, and feeds pebbles flowing from the bottom of chamber 11 into bucket elevator 19 for delivery into pebble inlet 7 and on into chamber 14. Combustion chamber 20 is positioned subjacent pebble heating chamber 14. Chambers 14 and 20 are separated by perforate support 25 through which combustion gas formed in chamber 20 ascends to pass in direct heat exchange relation with pebble mass 9 in chamber 14. Fuel gas, usually natural gas from line 6 and/or hydrogen recycle gas, from lines 13 and 65, described hereafter, is introduced through line 22 and mixed with oxygen from line 21 to form a combustion mixture in line 23 which is burned in combustion zone 20. Hot combustion gas formed in zone 20 ascends through perforate support 25 at a temperature in the range of 2200 to 3500° F. The temperature of the pebbles leaving zone 14, i. e., entering zone 11, is from about 1800 to 2800° F. and may be controlled to higher or lower levels by regulating the proportion of oxygen introduced through line 21, the proportion of hydrogen rich gas introduced from lines 13 and 65, and by regulation of the rate of pebble flow through chamber 14. Pebble temperatures may be lowered by introducing an inert gas diluent to the combustion chamber to effect reduction in flame temperature. Combustion gas having imparted heat to pebbles in zone 14 is passed as effluent from zone 14 through lines 15 and 17 to further utilization not shown, or through lines 15 and 44 as described hereafter. Methane feed stock, often natural gas, is introduced through line 48 into the lower portion of gas heating chamber 11, entering at a point below perforate gas distribution plate 5, and is passed therethrough in direct heat exchange relation with pebbles previously heated in zone 14, and is heated within from .1 to .5 second to a temperature within the range of 1800 to 2400° F., a more preferable temperature range being from 1900 to 2200° F. The extent of any hydrocarbon cracking in zone 11 is limited by the short contact time employed. I find usually that I may tolerate as much as 20 per cent cracking, when preheating methane in this manner, and I prefer in any case to limit the extent of cracking by minimizing the heating time. Pressure conditions in the pebble heater apparatus are preferably atmospheric or nearly so. Pressures from 2 to 6 p. s. i. g. are preferred, although pressures as high as 25 p. s. i. g. may be employed in some cases. Effluent hot gas from gas heating chamber 11 is passed through line 12 to a mixing T, or Venturi throat, 36, wherein it is quickly mixed with and heated by hot combustion gas formed by burning a hydrogen recycle stream, from a subsequent purification step described hereafter, with free oxygen. Hydrogen recycle gas from lines 24 and 26 is preheated in preheater 27 to a temperature usually within the range of 500 to 1200° F., and passed through lines 28 and 29 to line 31 wherein it is mixed with oxygen or an oxygen-rich combustion supporting gas introduced from line 32, and the resulting admixture passed to combustion zone 33. In some cases preheating may be unnecessary and hydrogen recycle gas may be passed from line 24 directly to line 29 through line 30. The hydrogen-rich gas is preferably burned with oxygen of purity in the order of 90 to 95 per cent, in a water cooled burner nozzle and in a combustion chamber adequately lined to withstand the required high temperatures developed. Preferred construction materials suitable for withstanding high

temperatures in the process of my invention are discussed later with reference to Figure 2. Combustion gas from zone 33 comprises steam, usually in larger amounts, together with some carbon dioxide. Combustion gas temperatures are controlled to within the range of 3200 to 5000° F. Such control is effected by introducing an excess of hydrogen recycle gas from line 29 so that some unburned hydrogen is present in the combustion gas. For example, I prefer usually to form a combustion gas in zone 33 at a temperature of from 3600 to 4200° F. and in so doing I introduce from 100 to 250 per cent excess hydrogen recycle gas to the combustion step. Effluent combustion gas from zone 33 is passed through line 34, usually at a temperature within the 3600 to 4200° F. range, into venturi 36 preferably at right angles to hot gases entering from line 12. Gases from lines 12 and 34 are passed into venturi 36 at linear velocities in the order of 100 to 400 feet per second. In passing through the Venturi throat the linear velocity of the gas admixture is accelerated to from 300 to 500 feet per second. The temperature of the gas passing from venturi 36 is regulated by the temperature of the preheated gas from line 12 and temperature of combustion gas from line 34 and is within the limits of 2400 to 3500° F., although a more preferable temperature range is from 2600 to 3200° F. Effluent gas from venturi 36 is maintained at the specific requisite temperature for a time within the limits of 0.001 to 0.05 second in reaction tube 37 attached to, or in close proximity to venturi 36. Acetylene is formed in reaction tube 37 in high yield, which yields may be attributed to the high temperature employed, and to a great extent to the presence of diluent gases from combustion zone 33, whereby undue degradation and/or hydrogenation of acetylene product is substantially prevented. The contact time of the reacting gas in zone 37 is necessarily short and is controlled, by immediately quenching effluent gas from zone 37 to below a temperature at which undesirable by-products are formed. This is done by passing effluent from zone 37 into mixing T or venturi 38, usually of the same type as venturi 36, and quickly quenching the acetylene product by admixing it therein with relatively cool hydrogen-rich recycle gas from line 39, steam or water spray from line 43 or flue gas from line 44, or any combination of any or all such gases entering through line 42. Effluent gas from venturi 38 is passed from venturi 38 at a temperature of about 1800 to 2300° F.

Operating in the manner described above, natural gas is quickly heated to a high temperature necessary for the acetylene forming reaction to proceed, is maintained at such conditions for the short contact requisite for acetylene formation, and thereafter quickly quenched to terminate its retention at such conditions, whereby acetylene is selectively formed in high yield and can be utilized as such, in a subsequent aromatics-forming step.

Acetylene-containing gas is passed from venturi 38 to aromatics-forming step 47, wherein light aromatic hydrocarbons, such as benzene, are formed in high yield together with relatively small amounts of diolefin hydrocarbons, and heavier aromatic hydrocarbons formed as by-product. The reaction in zone 47 is conducted by maintaining gases therein from venturi 38, at their existing temperature for a duration of from 0.05 to 5.0 seconds. I prefer usually to quench acetylene gas product in venturi 38 so that gas

from venturi 38 enters zone 47 at a temperature in the range of 1900 to 2200° F., and under such conditions a contact time within the limits of 0.2 to 3.0 seconds may be selected. Effluent from zone 47 is passed through line 48 and quenched to a temperature in the range of about 400 to 800° F. by admixture in line 49 with water spray introduced through line 51. The resulting admixture is passed to water quench tower 57 through lines 55 and 56 wherein it is contacted countercurrently with water introduced through lines 58 and 59, and cooled to a temperature usually within the range of 100 to 200° F. If desired, material in line 49 may first be passed through line 52, cooler 53, and line 54 to line 56, with or without water introduced through line 51. Water may be drained from zone 57 through line 62, and any heavy by-product oils removed through line 61. Product-containing gas is passed from zone 57 through line 63 to an absorber-stripper system, preferably of the conventional type employing a mineral seal oil absorbent. Material in line 63 is introduced to absorber 64 and passed therein countercurrently in relation to down-flowing fresh and/or stripped mineral seal oil introduced through line 71. Hydrogen-rich gas is passed from an upper portion of absorber zone 64 through line 65 for combustion in zone 33 and/or zone 20 as already described, and/or as a quenching gas in venturi 38, already described. Any excess recycle gas in line 65 may be withdrawn through line 66. Enriched absorber oil is passed through the lower portion of zone 64 through line 67 and introduced to stripper 68 maintained under distillation conditions whereby the rich oil is distilled and absorbed materials are liberated as vapors. Gaseous material is passed from stripper 68 to product separation means 70 comprising coolers, separators, distillation equipment, storage tanks and the like not individually illustrated, which can be used to effect a separation of various selected product fractions. Lean absorber oil is passed from the lower portion of stripper 68 through lines 69 and 71. Fresh absorber oil may be introduced to the absorber system through line 72. Selected product fractions include benzene withdrawn through line 73, toluene withdrawn through line 74, cyclopentadiene and other diolefins withdrawn through line 76, and a fraction containing light aromatic hydrocarbons such as styrene, methylstyrene, and xylenes, withdrawn through line 77. A relatively heavy fraction of aromatics comprising naphthalene and anthracene is withdrawn through line 78.

As already mentioned, the lining of the refractory equipment is important in view of the high temperatures and high linear gas velocities utilized, employed as already discussed. The lining of combustion zone 33, lines 12 and 34, venturi 36, reaction tube 37 and venturi 38 is necessarily highly resistant to abrasive action, and capable of withstanding the high temperatures of my process.

Preferred lining and insulating materials and the use of such materials in carrying out a preferred process of my invention are illustrated in Figure 2, which is a diagrammatic cross sectional view of the system represented in Figure 1 by lines 12 and 34, venturi 36, reaction tube 37 and venturi 38. Referring to Figure 2, effluent line 12 is rigidly attached to venturi 36 by flange 81. Combustion zone 33 is rigidly attached to line 34 and venturi 36 by flange 82. Reaction tube 37 is rigidly attached to venturi 38 by

flange 83 and to venturi 38 by flange 84. Line 12, venturi 36, line 34, reaction tube 37, and venturi 38 are all highly insulated and maintained in close proximity to each other to minimize heat losses, prevalent at the temperatures employed in the practice of this invention. Line 12 is lined with a dense, hard-burned, small-grained, high purity, supported corundum lining 88 to resist abrasion and this lining is backed up by a light weight insulating material 89, such as mullite or alumina. Outer jacket 90 may be any suitable steel. Combustion chamber 33 is lined with zirconia 91, partially stabilized with CaO or MgO and backed up by insulation 92 comprising zirconia and light weight mullite or alumina. Line 34 is insulated in the same manner as combustion chamber 33. The lining of venturi 36 is also fabricated preferably of stabilized zirconia 94, but of a very small grain, dense, hard-burned structure to resist abrasive effects of high gas velocities. It is preferable to back up the dense zirconia refractory with a light weight insulating zirconia, 96, for temperatures of about 3000° F., and higher, or below these temperatures with light weight mullite or insulating fire brick, not shown. Reaction tube 37 is preferably of the same construction as line 12 and may be backed with light weight alumina or mullite insulating brick, and with the usual standard insulating materials when temperatures are lower than about 2600° F. Venturi 38 may be fabricated similarly to venturi 36. Aromatics forming zone 47 is rigidly attached to venturi 38 by flange 87 and may be fabricated in a manner similar to that of reaction zone 37.

For convenience and clarity certain apparatus such as pumps, surge tanks, accumulators, valves, etc. have not been shown in the drawing. Obviously such modifications of the present invention may be practiced without departing from the scope of the invention.

As already described, a feature of my invention resides in the formation of aromatic hydrocarbons from acetylene at temperatures from 600 to 1000° F. above those ordinarily employed, and the advantages of this higher temperature operation have already been pointed out. I am able to utilize such high aromatic forming temperatures by operating in the presence of hydrogen. Under such conditions, dehydrogenation of acetylene with consequent carbon formation, and hydrogenation of acetylene to ethane with consequent low yields of desired product is substantially prevented, and higher and more efficient conversions of acetylene are obtained. Some hydrogenation of acetylene to ethylene may occur, but if so, it is in no way disadvantageous. The temperature conditions are chosen such that partial hydrogenation to ethylene is possible and favorable, but at which total hydrogenation of acetylene to ethane or of any ethylene to ethane, is not promoted. The contact time is so chosen that dehydrogenation of acetylene, and polymerization of acetylene is kept at a minimum, and so chosen that a minimum amount of unsaturates such as butadiene, cyclopentadiene, and C₆ dienes are formed together with high yields of light aromatic hydrocarbons particularly, benzene and toluene. Only minor amounts of heavier aromatic components, tars and the like are formed at these selected temperatures and contact times. Typical of preferred time-temperature relationships employed in the practice of the aromatics

5 forming step of my invention are indicated as follows:

Time, Sec.	Temp. ° F.
1.5 to 5.0	1,800
1.0 to 3.0	1,900
0.6 to 2.0	2,000
0.4 to 1.2	2,100
0.2 to 0.6	2,200
0.05 to 0.2	2,300

I am not certain as to the exact mechanism of the reaction taking place in the aromatics-forming step. However it is possible that, (1) 15 acetylene is first partially hydrogenated to ethylene as indicated by the equation

(2) ethylene and acetylene then co-polymerize 20 to form butadiene as indicated by the equation

and (3), butadiene thus formed co-polymerizes 25 with ethylene or acetylene followed by dehydrogenation and cyclization to benzene, as indicated by the following equations

30 In any case, some hydrogenation of acetylene to ethylene undoubtedly takes place under the conditions of my process and possibly contributes the high yields of benzene by virtue of its reaction with butadiene. Furthermore, the presence 35 of any ethylene formed has a stabilizing effect upon the reactant gases and may contribute to maintaining the low carbon yields obtained.

The amount of hydrogen present in the aromatics-forming step is important in that it is 40 advantageous that at least 40 per cent of the gas in the aromatics-forming step consists of hydrogen. Usually the amount of hydrogen produced in the acetylene-forming step is more than that 45 needed to supply the necessary hydrogen to the aromatics-forming step, and no hydrogen from any other source is required. However, it is sometimes advantageous to employ hydrogen as a quenching agent to cool gases entering the 50 aromatic-forming zone, and in such cases even larger amounts of hydrogen may be provided in the aromatics-forming chamber. Usually I prefer to employ some steam or water spray along with recycle hydrogen gas as a quenching agent. 55 Hydrogen recycle gas is most advantageously employed as a quenching gas in those cases wherein the amount of hydrogen formed in the acetylene forming step and passed to the aromatic forming step is below that desired, as 60 might be the case when heavier hydrocarbons comprise the stock feed to the acetylene forming step. I have found that hydrogen may comprise as high as 90 per cent of the gas in the aromatics forming step and may be present in even higher concentrations, although excessively high concentrations serve only to reduce the effective capacity of the chamber and auxiliary equipment.

Any gaseous hydrocarbon stock may be employed in the practice of my invention for conversion to acetylene. The process has a distinct 65 advantage, in that methane, or a methane-rich gas such as conventional dry natural gas, can be economically converted. The resulting acetylene-rich product is satisfactory in any case for use in the aromatic forming step. Lower tem-

peratures may be required for conversion of the heavier hydrocarbons to acetylene, but usually the conditions of the aromatic forming step are substantially unchanged.

My invention is illustrated by the following example. The reactants, their proportions, and other specific ingredients are presented as being typical and should not be construed to limit the invention unduly.

Example

Natural gas of the following composition

Component	Volume Percent
CH ₄	92
C ₂ H ₄	4
C ₂ H ₆	1
N ₂	3

is heated in the gas-heating chamber of a pebble heater apparatus to 2000° F. at a contact time of 0.3 second under a pressure of 4 p. s. i. g. Under such conditions of preheating, about 20 per cent cracking takes place. The composition of the gas leaving the pebble heater outlet is as follows:

Component	Volume Percent
H ₂	7.1
CH ₄	84.8
C ₂ H ₄	1.9
C ₂ H ₆ +C ₃ H ₈	3.3
N ₂	2.9
C+tar	1.9

¹ Carbon and tar-free basis.

² By weight.

Effluent gas is discharged from the gas heating chamber at a linear velocity of 200 feet per second into a Venturi throat. In a separate combustion chamber, a hydrogen-rich recycle gas of the following composition,

Component	Volume Percent
H ₂	84.2
CH ₄	1.0
N ₂	2.0
CO	2.7
O ₂	0.1

produced in a subsequent purification step, is admixed in 150 per cent excess with oxygen of 95 per cent purity, and the resulting admixture burned to produce combustion gas, comprising carbon dioxide and steam, at a temperature of 4000° F.

Combustion gas at 4000° F. is discharged from the combustion chamber into the venturi at a linear velocity of 150 feet per second and is rapidly mixed therein with the preheated natural gas to form an admixture at a temperature of about 3000° F. The accelerated linear velocity of the gas mixture passing through the Venturi throat is about 300 feet per second. The resulting effluent gas admixture is maintained at its existing temperature of 3000° F. in a reaction tube, for a period of 0.01 second and under these

conditions pyrolysis occurs to produce a product gas of the following approximate composition:

Component	Volume Percent ¹
H ₂	66.8
CH ₄	8.7
C ₂ H ₂	17.6
C ₂ H ₄ +C ₃ H ₆	3.0
N ₂	1.6
CO	2.2
O ₂	0.1
C+tar	18.7

¹ Carbon and tar-free basis.

² By weight.

15 The yield of acetylene per M. S. C. F. of natural gas feed is 315 cubic feet. Acetylene-containing product thus formed is rapidly quenched by admixture in a mixing T or venturi with relatively cool hydrogen-containing gas, usually a hydrogen recycle stream already described, from a temperature of 2950° F. to a temperature of 2100° F. and held at that temperature level for a duration of 0.8 second. Under such conditions the acetylene containing gas is converted to a crude aromatics product obtained in a yield of 1.0 gallon per M. S. C. F. of natural gas, containing about 70 per cent benzene, and 10 per cent toluene with the remaining product comprising cyclopentadiene and other diolefins in the C₄ to C₆ range together with other light aromatics such as xylenes, styrene and methyl styrene, and relatively minor amounts of heavier aromatics predominantly naphthalene and anthracene.

20 As will be evident to those skilled in the art, various modifications of this invention can be made, or followed, in the light of the foregoing disclosure and discussion, without departing from the spirit or scope of the disclosure or from the scope of the claims.

I claim:

1. A process for the manufacture of an aromatic hydrocarbon-containing product rich in benzene and containing diolefin hydrocarbons, comprising heating natural gas to a temperature in the range of from 1800 to 2400° F. for a time of from 0.1 to 0.5 second, admixing hydrogen with oxygen in regulated proportions and burning the resulting admixture to form combustion gas at a temperature within the range of 3200 to 5000° F., further heating said natural gas to a temperature within the range of 2400 to 3500° F. by admixing same with hot combustion gas from said burning and maintaining the resulting admixture at said temperature for a time within the limits of 0.001 to 0.05 second, whereby an acetylene-containing product is formed, quenching said acetylene-containing product to a temperature within the range of 1800 to 2300° F. by admixing same with cooler hydrogen, maintaining a concentration of hydrogen in the resulting quenched admixture of at least 40 volume per cent, and maintaining said resulting quenched product admixture at the last said temperature for a time of from 0.05 to 5.0 seconds whereby said aromatic containing product is formed, separating said product into selected fractions, and recovering said selected fractions as products of the process.

2. A process for the manufacture of an aromatic hydrocarbon-containing product rich in benzene and containing diolefin hydrocarbons having from 4 to 6 carbon atoms per molecule, toluene, xylenes, styrenes, naphthalenes and an-

thracenes, said process comprising heating natural gas to a temperature within the range of 1800 to 2200° F. within from 0.1 to 0.5 second, admixing a regulated proportion of hydrogen-rich gas described hereafter with oxygen and burning the resulting admixture to form combustion gas at a temperature within the range of 3600 to 4200° F., further heating said normally gaseous hydrocarbon to a temperature within the limits 2600 to 3200° F. by admixing same with hot combustion gas from said burning, maintaining the resulting admixture at said temperature for a time of from 0.001 to 0.020 second whereby an acetylene-containing product is formed together with by-product hydrogen, quenching said acetylene-containing product in direct heat exchange relation with a cooler quench gas described hereafter to a temperature within the range of 1900 to 2200° F. and maintaining the quenched product at the last said temperature in the presence of hydrogen in a concentration of at least 40 volume per cent for a duration of from 0.2 to 3.0 seconds whereby said aromatic-containing product is formed, separating hydrogen-rich gas from said aromatic-containing product and recycling a portion of same to said burning, recycling a portion of the hydrogen thus separated as said quench gas, separating a remaining portion of said aromatic-containing product into selected aromatic hydrocarbon and diolefin hydrocarbon fractions, and recovering said fractions as products of the process.

3. The process of claim 2 wherein said quench gas is supplemented with water.

4. A process for the manufacture of an aromatic hydrocarbon-containing product rich in benzene and containing diolefin hydrocarbons, comprising heating a normally gaseous hydro-

carbon to a temperature within the limits of 1800 to 2400° F., burning hydrogen with oxygen to form combustion gas at a temperature of at least 3200° F. and not higher than 5000° F., admixing normally gaseous hydrocarbon thus heated with said combustion gas in a proportion to form a resulting gaseous admixture at a temperature within the limits of 2400 to 3500° F., maintaining the resulting admixture at said temperature for a time within the limits of 0.001 to 0.05 second, whereby acetylene is formed as a chief product, quenching acetylene-containing product thus formed in direct heat exchange relation with a cooler quench gas described hereafter to a temperature within the range of 1800 to 2300° F. and maintaining the quenched product at the last said temperature in the presence of at least 40 per cent hydrogen for a time within the limits of 0.05 to 5 seconds, whereby a product rich in aromatic hydrocarbons is formed, separating a hydrogen-rich gas from said product rich in aromatic hydrocarbons and recycling at least a portion of the hydrogen thus separated as said quench gas, and recovering an aromatic hydrocarbon fraction as a product of the process.
